UNITED STATES PATENT OFFICE.

GEORGE HALE BARRUS, OF BROOKLINE, MASSACHUSETTS.

DRAINAGE SYSTEM.

1,192,369.

Specification of Letters Patent. Patented July 25, 1913.

Application filed November 18, 1912. Serial No. 872,876.

To all whom it may concern:

Be it known that I, GEORGE H. BARRUS, a citizen of the United States, and a resident of Brookline, in the county of Norfolk and State of Massachusetts, have invented certain new and useful Improvements in Drainage Systems, of which the following is a specification.

My invention relates to improvements in condensation drainage systems of steam heating apparatus comprising a multiple number of elements or units, and is particularly applicable to the revolving drying cylinders of paper making machines, and other machines of similar kind.

In paper machines and machines of similar character, the condensation within the drying cylinders is withdrawn through one of the two trunnions on which the cylinder revolves. This trunnion is made hollow and provided with two passages, one of which serves to admit steam for heating the cylinder, and the other serves to discharge the condensed water and waste steam resulting therefrom. There are two systems in common use for discharging the condensed water, viz., the "bucket" system and the "siphon" system. In the former a bucket, scoop or dipper, is attached firmly to the interior of the shell (sometimes being made as a part of the shell) and revolves with it. The bucket fills with water when at the lowest point, and when it revolves above the level of the trunnion the water which has been scooped up empties itself through a radial pipe or equivalent passage and then into the drain pipe within or at the end of the trunnion.

In the "bucket" system, if the drying cylinders are run at a low speed the drainage is not dependent on the difference in pressure between the steam in the cylinder and that in the return main because the water empties by gravity when the bucket, in the process of revolution, is elevated above the center. However, the centrifugal force on the water becomes considerable even with moderate speeds of the drying cylinders, thereby causing the centrifugal force to hold the water back until the bucket is elevated considerably above the center, thus shortening the time in which the water has to run out. At high speeds of the drying cylinders such as are used in the production of thin papers, the centrifugal force becomes so great that the action of gravity on the wa-

ter becomes either completely counteracted or so nearly so that it can not be depended on to produce effective drainage.

In the "siphon" system a "siphon" so called is connected to the drain pipe within the trunnion, one being in reality an extension of the other. The part within the cylinder is bent downwardly till it reaches very nearly to the bottom. The siphon pipe is stationary and the open end is sealed with water if the water inside is deep enough to cover it. With this arrangement it is evident that drainage upward through the siphon pipe is dependent on the difference of pressure between the cylinder and the return main which must be sufficient to lift the water from the end of the siphon to the center of the trunnion. If the difference of pressure becomes at any time insufficient to do this, the water is held back in the cylinders until the required difference is restored, and then the water is forced out in a "gulp". The discharge of water by the usual method of "siphon" drainage is therefore more or less irregular.

In either system, whether "siphon" or "bucket", it is customary to discharge water of condensation from the return main through an automatic steam trap which allows the water to be discharged without apparent loss of steam. One method of trapping the water is to provide a vertical loop in the outlet of the return main of sufficient height to balance the pressure in the return main.

In the usual siphon system, the drainage, as already stated, is not continuous at either low or high speeds of the drying cylinders. With the bucket system the drainage becomes very unsatisfactory at even moderate speeds, and fails altogether at high speeds. One of the objects of my invention is to produce such a continuous difference in pressure between the cylinders and the return main that the water will all be constantly and steadily discharged through the drainage pipe and no water will lie in the cylinder to a greater depth than the radial distance from the mouth of the siphon pipe or bucket to the inner wall of the cylinder.

In neither of the two usual systems as above described, and ordinarily applied is provision made for continuously freeing the cylinders of accumulations of air, and one of the leading objects of my invention is to

secure a circulation of steam completely through each drier in such a way as to free it of air, and to do this by such means as to prevent loss of steam which would 5 ordinarily occur with such a circulation.

With these two important objects obtained, a maximum amount of heat will be transferred from the steam to the metal of the drying cylinder, and the pressure within 10 the cylinder as well as the consumption of steam for doing the required amount of heating will be reduced to a minimum.

The main features of my invention are the dividing of the series of drying cylinders into two sections; supplying steam from the main source to the first section of cylinders; providing in the drainage pipe of each cylinder of the first section a definite size of passage so proportioned as to hold 15 back within these cylinders a sufficient steam pressure to obtain the required difference in pressure between the cylinders and the return main and allowing only such an amount of steam to pass through said drainage pipe 20 along with the water condensation to the return main as is necessary to secure constant and steady drainage of the water and air from said cylinders; separating from the water in the return main such steam 25 as has been passed thereto and supplying it to the second section of cylinders; providing in the drainage pipe of each cylinder of the second section a definite size of passage so proportioned as to maintain with 30 in these cylinders a maximum pressure consistent with their constant and steady drainage; separating the return main of the second section from the principal return main of the first section so that it discharges 35 independently to waste or to the hot well tank which receives the water discharged from the first section; and the adaptation 40 of the number of drying cylinders using steam from the principal return main to 45 the difference in pressure necessary for most efficient drainage of the water and air. In providing the definitely proportioned size of passage in the drainage pipes of both sections I find it advantageous to accomplish 50 this by having these drainage pipes considerably larger than the size required for such a proportioned passage, and then by inserting a constricted orifice, preferably in the form of a valve provided with a notch 55 or orifice of the proper size cut into its gate or seat, I am able to secure a ready means of clearing the pipe of any foreign matter which would lodge in the orifice, by simply opening the orifice valve for a short time and 60 allowing the foreign matter to be blown through. Where gate valves are used, they can be arranged either with a central orifice or with a notch cut in the edge of the gate. I find it advantageous to so construct these 65 orifices that their size can be easily and

quickly varied to suit the variation in conditions under which the machine is being used. In this way the proper difference of pressure between the cylinders and the return main can be obtained to lift the water 70 steadily at the proper rate, whether the machine is run at slow, moderate or high speeds. By forming the notch in the edge of the gate of a gate valve so that part of the notch may be closed by the valve seat, 75 I am able to provide a cheap and easily operated means of varying the size of the notch to suit the various conditions of use of the machine.

In the accompanying drawings, I have 80 illustrated in connection with a paper machine the preferred embodiment of my invention, and in said drawings, Figure 1 is a diagrammatic side elevation of a portion of a paper machine showing the drying cylinders and the steam pipe connections for supplying the steam to these cylinders; Fig. 2 is a diagrammatic side elevation of the same cylinders viewed from the same point, with the drainage pipe connections shown, 85 but omitting the steam pipe connections shown in Fig. 1, in order to avoid confusion through having too many pipes which lie close together, shown on the same drawing; Fig. 3 is a partial end elevation of a portion 90 of Figs. 1 and 2 showing both the steam pipes and the drainage pipes; and Fig. 4 is an enlarged partial view of a standard gate valve showing the notch which I make in the edge of the gate.

Referring now to the drawings, what is known as the "wet end" of the machine is at the left hand side, and beginning from this end I have indicated the first three of the drying cylinders by the numerals 1, 2, 3, 95 and the remaining cylinders by the numeral 4.

5 indicates the steam supply main leading from which are the individual steam pipes 110 each of which supplies steam to its respective cylinder, being connected at its upper end to a double fitting 7, from which the horizontal pipe 8 projects into, and has a running joint connection with, the revolving trunnion 9. The steam is thus conveyed 115 through the hollow trunnion 9 to the interior of the drying cylinders as clearly shown in Fig. 3. Provided in each of the steam pipes 6 is a valve 10 for separately cutting off the steam supply from each cylinder.

In Fig. 2, 11 indicates the drainage main to which are connected separate pipes 12 leading from each of the drying cylinders, each of the separate pipes 12 being connected at its upper end to a separate passage, distinct from the steam passage, in the double fitting 7, the drainage being brought to this separate passage by a siphon pipe 13 which passes concentrically through the hollow trunnion 9 to the interior of the drying cyl-

inder where it curves downward until its open end is just above the bottom of the interior of the cylinder.

The steam supply and drainage connections thus described are adapted to the use of the usual system for supplying steam to the drying cylinders of a paper machine and draining by the siphon system the condensed water therefrom, suitable traps being usually employed in the drainage main or in the separate drainage pipes to prevent steam from being carried to waste there. A drainage main which ultimately connects to the hot well. In applying my system to the machine as already described, I provide a "waste steam" pipe or "secondary supply main" 14 which lies above the drainage main 11 and is connected thereto on its upper side by two or more pipes 15, 16, as is clearly shown in Fig. 1, where the drainage main 11 has been shown in dotted lines, as this view refers entirely to the steam piping, the pipe 11 here shown, however, being exactly the same as pipe 11 of Fig. 2 where it is shown in solid lines. Connecting the waste steam pipe 14 to the individual steam supply pipes 6 of cylinders 1, 2 and 3, are pipes 17, said pipes 17 connecting to the pipes 6 above the valves 10, and each of the pipes 17 being provided with a valve 18. By shutting off the valves 10 of the pipes 6 leading to cylinders 1, 2 and 3, and opening the valves 18 in each of these three pipes 17 leading from the waste steam pipe 14, the said cylinders are cut off from the principal steam supply main and are instead supplied with only such steam as comes from the drainage main.

In Fig. 2 I have shown a separate drainage pipe 19 with three connections 20 leading therefrom to the three drying cylinders 1, 2 and 3, the said pipes 20 each having a valve 21 in it and connecting to the drainage pipes 12 of the said cylinders just above the valves 22; the valves 22 being used to shut off the drainage pipes 12 of these cylinders from the drainage main 11, so that the drainage from these three cylinders can be taken through the pipe 19 to the hot well, or if desired, by means of the pipe 23, to the atmosphere or any other place it is desired to take it.

Placed in each of the drainage pipes 12 of each of the drying cylinders 1, 2, 3, 4, etc., is a valve 24 in the gate of which is a notch 25 formed in the edge thereof, as shown in Fig. 4. In practice I find that in order to obtain the best results it is necessary not only to be able to slightly vary the size of the notch for different conditions of use of the machine but also to have the notches in these valves of some of the cylinders different in size from those in others, the notch in the valves at the wet end of the machine 22 being somewhat larger than at the dry end.

To adjust the machine for operation in accordance with my improved system the valves 10 and the valves 22 of the cylinders 1, 2 and 3 connecting the cylinders with the main steam supply and drainage pipes 70 are closed, and the valve 18 from the secondary supply main and the valves 21 of the drainage pipe system are open so that cylinders 1, 2 and 3 will be cut from the main supply and drainage pipes to which 75 all the other cylinders are connected. The orifice valves 24 for all the cylinders will be properly proportioned and adjusted to give the desired difference in pressure between the cylinders and their drainage 80 pipes.

The water of condensation formed in the cylinders 4 will be taken along with only such an amount of steam which is necessary to secure continuous drainage into the drainage main 11, the steam separating from the water in the main and passing into the steam pipe 14 from which it is supplied to the cylinders 1, 2 and 3. The water of condensation in these cylinders is discharged 85 through the secondary drainage pipe 19 to the hot well or other desired point.

It is to be noted that the main object of the orifice valves or properly proportioned passages in the drainage pipes, is to secure 95 a suitable difference of pressure between the steam supply and the condensation return mains, or between the cylinders themselves and the return mains, with a minimum loss of steam that will secure a steady and continuous circulation which will not only carry out the water of condensation as it is formed, but also any air that is in the drying cylinders. In the usual drainage systems the difference in pressure between the 105 steam in the supply pipe or in the cylinders, and that in the return main, is only a pound or so, where the siphon system of drainage is used, and even less where the bucket system is employed. This is due to 110 the steam that blows through the rotating connections between the cylinders and the drainage pipes and thus passes into the drainage main in which it is held by the usual trap through which the water is discharged in passing from the return main to the hot well. By providing properly proportioned passages in the drainage pipes, 115

of the first section of the drying cylinders I hold the amount of steam passing through 120 these drainage pipes to a predetermined amount, and even that which does pass through the said passages into the return main is then taken from the upper part of the said return main (into which it is forced 125 by the water of condensation being heavier and settling to the bottom of said pipe) and used for heating the second section of the drying cylinders, the orifice valves or properly proportioned passages in the drain- 130

age pipes of these cylinders permitting only the small amount of this waste steam to pass through them that is necessary to secure a steady drainage of the water of condensation and air therefrom.

It is to be noted that I do not use the water in the return main for heating the second section of cylinders, this water being trapped as usual and passed to the hot well or other desired place of disposal.

In practice I have found in the case of a certain paper machine with three of the drying cylinders supplied with waste steam in accordance with my system, that with steam in the principal supply main at 6 pounds pressure there was only 3 pounds pressure in the return main, thus giving a drop in pressure of 3 pounds to secure drainage of the water of condensation and the air from the first section of the drying cylinders, while with the waste steam supplied to these three cylinders shut off, there was a drop of less than one pound pressure between the supply and the return main, which was not enough to steadily and continuously force the water up through the siphon pipes. In another machine employing my system, with 12 pounds pressure in the principal supply main and with three drying cylinders supplied with the waste steam there was only 8 pounds pressure in the return main, thus showing a drop of 4 pounds to insure steady drainage of the cylinders of the first set.

I have also found in practice that in a certain machine, when using my system with only two drying cylinders supplied with the waste steam, at the end of a 24 hours' run there was only 4700 pounds of water remaining in the drying cylinders, whereas when the usual system of drainage without traps was used, there was 11,000 pounds of water remaining in the drying cylinders after a 24 hours' run; and when the usual system with traps was used, there was 207000 pounds after a 24 hours' run.

It is to be noted that I do not confine myself to the utilization of the "waste steam" in cylinders occupying any particular position in the machine, as the ones chosen for its use may be situated anywhere. It is also to be particularly noted that I do not confine myself to having all or any of the cylinders which are provided with proper connections for utilizing waste steam also provided with connections for using steam from the main source of supply. However, I prefer in the first application of my system to any particular machine where the machine or the conditions are different from those on which I have previously made exact determinations as to the best arrangements to secure the best results, to provide one or more of the cylinders with double sets of connections, as it is necessary in obtaining the best

results to proportion the number of cylinders and the size of the constricted passages or orifices not only to each other, but also to the pressure and dryness of the steam supply and to other factors varying with the conditions of the material on which the drying cylinders act. By having double connections to some of the cylinders with valves in these connections it is possible to easily vary the number of cylinders using waste steam not only for the purpose of determining what is the best number under any particular condition, but also to vary the number as the conditions themselves vary. Also, by having the orifices adjustable as to size, I am able not only to vary them to give the best results under any particular conditions, but also to make variations to suit variations in conditions.

While other systems have been proposed and used, in which a suitable drop in pressure between the cylinders and the drainage main is obtained by the use of individual traps or similar appliances for creating such a drop in pressure in the drainage main, it is to be noted that in my system I do not employ any such complicated means.

I have shown my invention applied to a stack of cylinders having a siphon drainage system, but it is of course understood that the invention is not confined to the siphon system alone, but may be used in conjunction with other systems, such for instance as the bucket system above described.

Claims:-

1. In a drainage system the combination of a multiple number of steam heating units divided into two or more sets, a principal drainage main, individual drainage connections between each of the said units of one set and said principal drainage main, a secondary drainage main, individual drainage connections between each of the units of a second set and said secondary drainage main, means for supplying steam to the first of said sets of units, means for permitting a predetermined amount of said steam to pass along with the water of condensation to the said principal drainage main, means for separating from the said water said steam so passed, means for supplying said steam so passed to the second of said sets of units, and independent means for each unit of said second set for causing a predetermined difference in pressure to exist between the said units and the said secondary drainage main.

2. In a drainage system the combination of a multiple number of steam heating units divided into two or more sets, a principal drainage main, individual drainage connections between each of the said units of one set and said principal drainage main, a secondary drainage main, individual drainage connections between each of the units of a second set and said secondary drainage main,

means for supplying steam to the first of said sets of units, means for causing a predetermined difference in pressure to exist between each unit of said first set and said 5 principal drainage main and for permitting a predetermined amount of said steam to pass along with the water of condensation to the said principal drainage main, means for separating from the said water said 10 steam so passed, and means for supplying said steam so passed to the second of said sets of units.

3. In a drainage system the combination of a multiple number of steam heating units 15 divided into two or more sets, a principal drainage main, individual drainage connections between each of the said units of one set and said principal drainage main, a secondary drainage main, individual drainage 20 connections between each of the units of a second set and said secondary drainage main, means for supplying steam to the first of said sets of units, means for causing a predetermined difference in pressure to exist 25 between each unit of said first set and said principal drainage main and for permitting a predetermined amount of said steam to pass along with the water of condensation to the said principal drainage 30 main, means for separating from the said water said steam so passed, means for supplying said steam so passed to the second of said sets of units, and independent means 35 for each unit of said second set for causing a predetermined difference in pressure to exist between the said units and the said secondary drainage main.

4. In a drainage system the combination of a multiple number of steam heating units 40 divided into two or more sets, means for supplying steam to one of said sets of heating units, a principal drainage main, means for passing a predetermined amount of said steam along with the water of condensation 45 to said principal drainage main, means for separating from said water said steam so passed, means for supplying said separated steam to the units of the second of said sets, and a secondary drainage main, connections 50 between the units of said second set and said secondary main, means for causing a predetermined difference in pressure to exist between said second set of heating units and said secondary drainage main and for maintaining 55 the pressure in said secondary drainage main at least equal to atmospheric pressure.

5. In a drainage system the combination of a multiple number of steam heating units 60 divided into two or more sets, a primary steam main with connections therefrom to supply each of said units of one set with steam, a primary drainage main, connections from each of said units of the first set to said primary drainage main, said connec-

tions having a constricted passage in each for maintaining a predetermined difference in pressure between said units and said drainage main and through which a predetermined amount of steam is passed along 70 with the water of condensation to said drainage main, means for separating from said water said steam so passed and supplying it to the heating units of a second of said sets, a secondary drainage main and 75 connections from said second set of heating units to said secondary drainage main.

6. In a drainage system the combination of a multiple number of steam heating units divided into two or more sets, a primary 80 steam main with connections therefrom to supply each of said units of one set with steam, a primary drainage main, connections from each of said units of the first set to said primary drainage main through 85 which a predetermined amount of steam is passed along with the water of condensation to said drainage main, means for separating from said water said steam so passed and supplying it to the heating units of a second 90 of said sets, a secondary drainage main, and connections from said second set of heating units to said secondary drainage main, said last mentioned connections having a constricted passage in each maintaining a predetermined difference in pressure between 95 said units and said secondary drainage main.

7. In a drainage system the combination of a multiple number of steam heating units divided into two or more sets, a primary 10 steam main with connections therefrom to supply each of said units of one set with steam, a primary drainage main, connections from each of said units of the first set to said primary drainage main, said connections having a constricted passage in each for maintaining a predetermined difference in pressure between said units and said drainage main and through which a predetermined amount of steam is passed along 110 with the water of condensation to said drainage main, means for separating from said water said steam so passed and supplying it to the heating units of a second of said sets, a secondary drainage main and 115 connections from said second set of heating units to said secondary drainage main, said last mentioned connections having a constricted passage in each for maintaining a predetermined difference in pressure between 120 said units and said secondary drainage main.

8. In a drainage system the combination of a multiple member of steam heating units divided into two or more sets, a primary 125 steam main, connections therefrom to each of said units of the first set, a primary drainage main, connections from each of said units to said drainage main, said connections being each provided with a constricted pas-

- sage exterior to its heating unit through which a predetermined amount of steam is passed along with the water of condensation to said drainage main, means for separating 5 said water and steam, supply connections to each unit of said second set for supplying the separated steam to said units, a secondary drainage main, connections between the units of said second set and said secondary 10 main, said connections being provided with constricted passages exterior to the said heating units, and means for maintaining pressure in said secondary drainage main equal at least to atmospheric pressure.
- 15 9. In a drainage system the combination of a multiple number of steam heating units divided into two or more sets, means for supplying steam to the units of one of said sets, a principal drainage main, pipe connections between each unit of said set and said drainage main, each connection being provided with a gate valve having in its gate an orifice smaller than the cross-sectional area of said connection for maintaining a 20 predetermined difference in pressure between each unit and said drainage main and for permitting a predetermined amount of steam to pass along with the water of condensation to said drainage main, means for separating 25 said water and steam and for supplying said steam to the units of another set.
10. In a drainage system the combination of a multiple number of steam heating units divided into two or more sets, means for supplying steam to the units of one of said sets, a principal drainage main, pipe connections between each unit of said set and said drainage main, each connection being provided with a gate valve having in the 30 edge of its gate a notch having a cross-sectional area smaller than the cross-sectional area of said connection for maintaining a predetermined difference in pressure between each unit and said drainage main and for permitting a predetermined amount of steam to pass along with the water of condensation to said drainage main, means for separating said water and steam and for supplying said steam to the units of another 35 set.
11. A drainage system for a plurality of heating units comprising means for supplying 40 said units with steam, a drainage main for said units, individual connections between each of said units and said drainage main, said connections being each provided with a constricted passage for maintaining a predetermined difference in pressure between the individual units and said drainage main whereby such pressure will effectually discharge the water of condensation from each unit. 45
12. A drainage system for a plurality of heating units comprising means for supplying said units with steam, a drainage main for said units, individual connections between each of said units and said drainage main, a gate valve in each of said connections having an orifice in its gate smaller than the cross-sectional area of the said connections for maintaining a predetermined difference in pressure between the individual units and said drainage main whereby such pressure will effectually discharge the water of condensation from each unit. 50
13. In a drainage system the combination of a multiple number of steam heating units divided into sets, means for supplying steam to the units of one of said sets, a principal drainage main, connections between said drainage main and each of said units, each of said connections being provided with a constricted passage permitting a predetermined amount of steam to pass along with the water of condensation to said drainage main, means for separating said water and steam, connections between said main and the heating units of a second set for supplying steam thereto, connections between the units of said second set and the main source of steam supply, connections between the units of said second set and said principal drainage main and valves in all of said connections of said secondary units for connecting at will with either source of supply or either drainage main. 55
